PRESSURE PUMP

Eugene L. Kilbourn, Marshall, Mich., assignor to
Progressive Dynamics, Inc., Marshall, Mich.

Filed Oct. 14, 1966, Ser. No. 4,285

Term of patent 14 years

(Cl. D52—6)

FIG. 1 is a perspective view of a pressure pump, showing my new design.

FIGURE 2 is another perspective view thereof, but showing the pump body fragmentarily and the gauge knob in extended position.

FIG. 3 is a side elevational view thereof with a fragmentary showing of the pump body, the rear, right and left elevational views thereof being the same in appearance.

FIG. 4 is a top plan view.

The essential features of the design reside in the portions shown in full lines.

I claim:

The ornamental design for a pressure pump, substantially as shown and described.
